G. C. COCHING.
COMBINED EYE SHADE AND REFLECTOR.
APPLICATION FILED AUG. 11, 1919.

1,353,630.

Patented Sept. 21, 1920.

UNITED STATES PATENT OFFICE.

GREGORIO C. COCHING, OF MANILA, PHILIPPINE ISLANDS.

COMBINED EYE-SHADE AND REFLECTOR.

1,353,630.

Specification of Letters Patent. Patented Sept. 21, 1920.

Application filed August 11, 1919. Serial No. 316,744.

To all whom it may concern:

Be it known that I, GREGORIO C. COCHING, a citizen of the P. I., residing at Manila, Philippine Islands, have invented certain 5 new and useful Improvements in Combined Eye-Shades and Reflectors, of which the following is a specification.

This invention relates to a combined eye shade and reflector.

10 The main object of the invention is to provide a device which will afford maximum light to the user at a minimum expense.

Another object is to provide a device of this character which will concentrate the 15 light on the object to be inspected.

Another object is to provide a simple and efficient device for rendering valuable ocular assistance in all kinds of work by the use of which the wearer can clearly see the 20 work in hand with a comparatively cheap grade of light, such as a kerosene lamp or a low watt electric light.

Another object is to provide such a device which when used, will permit one good 25 light to supply ample light for twenty or thirty persons, provided each person be equipped with one of these devices.

With the foregoing and other objects in view, which will appear as the description 30 proceeds, the invention resides in the combination and arrangement of parts and in the details of construction hereinafter described and claimed, it being understood that changes in the precise embodiment of the 35 invention herein disclosed may be made within the scope of what is claimed without departing from the spirit of the invention.

In the accompanying drawings:—

40 Figure 1 represents a perspective view of this improved device shown applied,

Fig. 2 is a top plan view of the device shown removed, the dotted lines indicating the swinging of the wings into folding position,

45 Fig. 3 is a front elevation of the device with parts broken out for convenience in illustration,

Fig. 4 is a rear elevation showing one of 50 the wings in operative right-angular position, and the other opened out,

Fig. 5 is a detail vertical section, and

Fig. 6 is a detail horizontal section with one of the wings shown at right angles to 55 the body portion in full lines, and in opened position in dotted lines.

The combined shade and reflector 1 constituting this invention comprises a rectangular frame 2, in which is mounted a mirror 3, the reflecting face being disclosed outwardly and its inner or rear face 4 coated with a suitable light softening paint, any desired color being used, preferably green.

The upper edge of the frame 2 has a rearwardly right-angularly disposed plate 5 secured thereto, being here shown made integral with the upper frame portion as shown in Fig. 5. This plate 5 has its rear edge curved to conform to the shape of the forehead of the user, and is provided on said curved portion with a flange 6, which fits snugly against the forehead of the user, and assists in holding the reflector in proper vertical position, the plate 5 operating as a spacer. This plate is shown equipped with a plurality of ventilating apertures 7 which are graduated, decreasing in size from the ends toward the center of the plate, although they need not necessarily be so formed.

80 Wings 8 are hingedly connected to the ends of the frame 2 and are preferably composed of nickel-plated sheet metal, made substantially triangular in form, with their lower edges curved as shown at 9. The 85 outer corners of these wings 8 have transversely arranged slots 10 formed therein to receive fastening straps 11 which are looped through said slots and secured by stitching or otherwise.

90 One of the straps 11 is preferably provided with a buckle 12 at its free end, and the other strap provided with longitudinally disposed apertures 13 for connection with the buckle by means of which the device 95 is secured to the head of the user and adjusted to fit different sized heads.

The wings 8 are so hinged to the frame 2 as to permit them to be folded flat against the outer face of the mirror 3 when not in 100 use, and when in use to extend at right angles toward the rear from the ends of said frame, as is shown in Fig. 2.

The frame 2 and wings 8 together with plate 5 may be constructed of any suitable 105 metal, and are preferably nickel-plated to render the device attractive and also to avoid abrasion of the head of the user.

In the use of this device, it having been applied as shown in Fig. 1, with the reflecting surface 3 arranged outwardly, and it 110 is desired to inspect an article 14 placed in

- the dark or any desired position, relative to the light L, which is here shown in the form of an electric bulb, the user positions his head so that the light rays will shine 5 against the mirror 3 and be deflected on to the object 14 to be inspected, thereby concentrating the light rays on this object, and enabling the wearer of the reflector to see every part of it clearly.
- 10 This combined shade and reflector may be used for various purposes, and it is especially useful for draftsmen, clerks, watchmakers, dentists, and the like.
- 15 It will be well understood that when a number of persons in the same room are equipped each with one of these devices, a single light or lamp of any kind will supply sufficient illumination for all of them.
- 20 From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.
- 25 Having thus fully described my invention, what I claim as new and desire to secure by Letters Patent, is:—
- 30
- 35 1. An eye shade comprising a frame having a mirror mounted therein with its reflecting face disposed outwardly, connect-

ing means carried thereby, and a curved forehead engaging member mounted on its upper edge and extending in a plane at right angles thereto.

2. An eye shade comprising a rectangular frame having a mirror mounted therein with its reflecting face disposed outwardly, connecting means carried by its ends, and a curved forehead engaging member mounted on its upper edge and extending in a plane at right angles thereto.

3. A device of the class described comprising a reflector, a plate extending rearwardly at right angles from the upper edge thereof, a longitudinally curved flange carried by said plate, and wings hinged to the end of said reflector to fold flat against its outer face when not in use and being held at right angles to its rear face when in operative position.

4. A device of the class described comprising a rectangular reflector, a plate extending rearwardly at right angles from the upper edge thereof, a longitudinally curved flange carried by said plate, substantially triangular wings hinged to the ends of said reflector to fold flat against its outer face when not in use and to be held at right angles to its rear face when in operative position.

In testimony whereof I affix my signature in presence of two witnesses.

GREGORIO C. COCHING.
